UNITED STATES PATENT OFFICE.

SAMUEL B. WILLIAMS, JR., OF BROOKLYN, NEW YORK, AND HERBERT L. BOSTATER, OF WEST NEW YORK, NEW JERSEY, ASSIGNEES TO WESTERN ELECTRIC COMPANY, INCORPORATED, OF NEW YORK, N. Y., A CORPORATION OF NEW YORK.

TESTING SYSTEM.

Application filed February 5, 1919. Serial No. 275,074.

To all whom it may concern:

Be it known that we, SAMUEL B. WILLIAMS, Jr., and HERBERT L. BOSTATER, citizens of the United States, residing at Brooklyn, in the county of Kings and State of New York, and West New York, in the county of Hudson, State of New Jersey, respectively, have invented certain new and useful Improvements in Testing Systems, of which the following is a full, clear, concise, and exact description.

This invention relates to electrical testing systems, and more particularly to testing systems capable of use in connection with telephone systems employing connecting apparatus common to one group of apparatus, to connect an individual set thereof with an individual set of another group of apparatus, with which the connecting apparatus may be associated.

A telephone system employing automatic distribution of calls between calling subscribers and answering operators through the medium of line finders and selectors is shown, and one example of such a system is disclosed in a patent of Samuel B. Williams, Jr., No. 1,304,641, dated May 27, 1919. In automatic call distributing systems it is usual to provide a terminal bank containing multiple sets of a large number of subscribers' lines. Each line has a number of terminal sets individual thereto, located horizontally across the bank and available to a number of different line finders; the line finders being so arranged as to connect with the terminals of all the subscribers' lines in the multiple bank. Each of the line finders is connected to a particular selector, and a group of these selectors are arranged to pass over a similar terminal bank containing multiple terminal sets of a number of cords or trunks extending to different operators' positions, a terminal set of each such cord or trunk being available to each of the selectors. Upon a subscriber removing his receiver from the hook switch in calling, an idle line finder is actuated to engage one of its brush sets with the terminal set of such line available thereto, and to extend the connection to the proper brush set of its associated selector. The selector searches over its terminal bank until such brush set encounters the terminals of an idle cord or

trunk terminating before an answering operator, and stops thereon, thus completing the connection of the calling subscriber's line to an answering position. The line finder involved and the particular selector connected thereto thus serve as connecting apparatus between the calling subscriber's line and the cord or trunk extending to an answering operator's position.

Each trunk has a signal associated therewith and operated on connection of a calling line with such trunk to indicate that a subscriber is calling. Should a line be connected with a trunk at a time when such line is not in use, due to an abnormal condition of line, the trunk signal would be operated in the same manner, although no response would be obtained to an operator's challenge. The signal is known under these conditions as a permanent signal. It is highly desirable that the line causing the trouble should be readily located and removed from service in such a way that like difficulties will not recur pending the restoration of the line to its normal condition. It is further desirable that such location should be made quickly in order that the line finder, the selector, and the trunk involved will not be engaged for an excessive period; thus reducing the available equipment and impairing the efficiency of the system.

In absence of the present system it would be necessary in such cases to visit in turn each of the selectors having a multiple of the involved trunk until the selector connected to the terminals of such trunk were located. From this selector the particular line finder connected thereto would be found, and such line finder visited. The particular set of terminals on which this line finder rests would next be noted, and the number of the line thus identified. This line is then removed from service, and prevented from effecting the engagement of other apparatus therewith by means of a trouble cord in the usual manner and the line finder manually restored to normal. Such a method is slow and the liability of error is considerable.

The principal object of the present invention is to provide a testing system capable of application to telephone systems employing a plurality of sets of connecting apparatus common to a group of sets of appa-

ratus in which each set of connecting apparatus is arranged to connect with any set of such group, by which any particular set of connecting apparatus connected with any 5 set of such group may be rapidly and accurately located. In accordance with this feature of the invention individual test terminals are provided for each set of connecting apparatus adapted to connect with the 10 sets of apparatus of the group, together with means by which testing current is supplied to the test terminal of a set of connecting apparatus connected to a set of apparatus of the group, and means cooperating 15 with the test terminals to determine the particular connecting apparatus involved in the connection.

Another object of the invention is to provide a testing system having a testing circuit 20 associated with a circuit to be tested in which the flow of testing current is such that the detection of the testing current is insured.

In accordance with this feature of the invention two transformer coils are provided and arranged for unsymmetrical connection by three conducting paths in such a manner that flux produced in the core of the first transformer coil will produce an effective 30 flux in the core of the second transformer coil by means of currents flowing over three circuits, each including a different pair of the three conducting paths and each of the three paths having current flowing thereover 35 so long as all of these three circuits are maintained. The circuit arrangement is also preferably such that an effective flux will, also be produced in the core of the second coil whether one, two or three of these circuits be maintained at the same time.

Other objects and features of the invention, not specifically mentioned above, will be apparent from the following specification and annexed drawing illustrating diagrammatically one embodiment of the present invention as applied to an automatic call distributing telephone system.

In the particular embodiment of the invention illustrated, a subscriber's station A is shown having a pair of line conductors 10 and 11, extending to a central office. A line relay 12, a cut-off relay 13, and a plurality of calling jacks, such as 14, individual to the line are provided. The line relay 12 is ordinarily operated over a circuit extending from battery, left-hand winding of relay 12, left-hand contact of relay 13, conductor 11, apparatus at substation A, conductor 10, and thence through the right-hand contact 60 of relay 13, and right-hand winding of relay 12 to ground.

In call distributing systems as applied to large exchanges, it is usual for a calling line to be extended to an answering operator, through a line finder associated with a

selector which selects an idle cord within its bank, this cord terminating before an answering operator, and having a calling plug by which a call can be extended to any desired line. Such an arrangement is illustrated, and the line conductors 10 and 11, and the test conductor 15 of the subscriber's line are multiplied to an individual set of terminals in a multiple terminal bank available to a number of line finders, any one of which is designed to extend the particular subscriber's line to an answering operator. Two such line finders, LF and LF' of the usual type, are shown in the present instance. The closure of the contact of relay 12 causes the line LF to seize the terminals 18 of the calling line substantially as disclosed in the Williams patent above noted. As further disclosed in the above-noted patent, the cord selector CS is caused to seize an idle cord or trunk extending to an idle operator's position herein shown as the associated circuit connected to the terminal set 21. The operator's telephone set is next automatically connected to the trunk 90 through the contacts 24 and 25 of a sequence switch, termed for convenience SS₂, when this switch is moved to position 7 as disclosed in the patent mentioned. A circuit is also closed from ground, interrupter 29, contact 23 of sequence switch SS₂, conductor 28, contact 26 of another sequence switch SS₃, and lamp 27 to grounded battery. The lamp 27 is individual to the trunk concerned, and the flashing signal given by this lamp serves 100 to identify the trunk over which a call has been extended to the particular answering operator.

A sequence switch SS₁ having a contact 100 is associated with the finder LF and its associated selector CS, and operates in such a manner as to close this contact 100 just subsequent to the stopping of the brush set 16 upon the terminal set 18 of line A. This closure takes place at position 4₂ and is 110 maintained until position 12₂, and provides an operating circuit for the cut-off relay 13, extending from grounded battery, contact 100, sleeve brush of brush set 16 and sleeve terminal of terminal set 18, conductor 15, 115 and winding of relay 13 to ground. Busy potential is also placed upon the sleeve terminals of the multiple jacks and also upon the sleeve terminals of the multiples of line A in the line finder contact banks. The operation of relay 13 opens the circuit 120 of line relay 12, which releases.

On the engagement of the tip and ring brushes of the selector CS with the tip and ring terminals of set 21, and consequent 125 movement of the contacts 24 and 25 of sequence switch SS₂ into their seventh position, the supervisory relay 69 is operated over a circuit extending from grounded battery, lower left-hand winding of repeating 130

coil 56, winding of relay 69, contact 23 of sequence switch SS_2 in position 7, engaged ring terminal and brush of selector CS, engaged ring brush and terminal of finder 5 LF, conductor 11, left-hand winding of induction coil, hook switch, and transmitter of station A, conductor 10, engaged tip terminal and brush of finder LF, engaged tip brush and terminal of selector CS, contact 10 24 of sequence switch SS_2 in position 7, and upper left-hand winding of repeating coil 56 to ground. A circuit is also provided through contact 98 of sequence switch SS_2 between positions 1 $\frac{3}{4}$ and 18 $\frac{1}{4}$, and effects 15 the illumination of the supervisory lamp 60 when the supervisory relay 69 is deenergized during such interval, this circuit extending from grounded battery, resistance 42, lamp 60, and contact 98 of sequence switch SS_2 20 between positions 1 $\frac{3}{4}$ and 18 $\frac{1}{4}$ to ground. On operation of relay 69, however, over the circuit previously mentioned, illumination of the lamp is prevented due to a short circuit completed about this lamp by the 25 closure of the contact of relay 69. On opening the operating circuit of relay 69, as for example by restoring the receiver to the switch-hook at station A, the lamp 60 is, however, illuminated to indicate that dis- 30 connection is desired by station A.

In the present situation the relay 69 being energized, prevents the illumination of lamp 60. The operator, under ordinary conditions, now obtains the number of the 35 called line and completes the connection in the usual manner. It sometimes occurs, however, that the operator obtains no response either to her request for "Number please" or to her subsequent challenge "Are 40 you calling?" although the lamp 60 is not lighted. The failure of the operator to obtain a reply indicates that something is the matter with this line. This condition is known as a permanent signal in systems 45 of this type. This condition may arise, for example, by the subscriber leaving his receiver off the hook, by conditions producing a short circuit between the line conductors 10 and 11, or by grounding thereof under 50 certain conditions. It is obviously desirable to determine what line is in trouble in order to remove the trouble and to free the line finder and selector involved in the connection so that they can be used in extending 55 other calls.

In the absence of any special testing equipment, in order to locate the line causing the permanent signal, it would be necessary to visit in turn each of the cord selector frames until the selector connected to the particular trunk or cord reported by the operator is found. From this selector it would be necessary to trace back to the particular line finder connected thereto, and 60 then to note the position of the terminal set 65 on which the brush set of such line finder rests, and from this identify the number of the line involved. This line may then be removed from service by the use of a trouble cord, in the usual manner, which serves to 70 provide a trouble test for all the multiples of such line. To simplify this procedure and to save time as well as to decrease the liability of error, the present invention contemplates the provision of a testing contact bank 35. Terminals individual to each of the line finders are arranged in this bank and connected to the tip and ring brushes of the brush sets of their respective line finders. A brush set 36 is designed to 75 pass over this contact bank and to engage one set of contacts at a time, the number of the line finder whose test terminals are engaged at any time being denoted by the number on a designation strip 37 associated 80 with the bank 35, indicated by a pointer 38 movable with the brush set 36. This bank is for testing purposes and would in practice be located convenient to the switchman, and a number of trunks would be provided between the answering positions of the main switchboard and the switchman's desk. The terminal set individual to line finder LF is 85 designated as 39.

The jack 40 of one such switchman's trunk 90 has been indicated and an operator having a trunk giving a permanent signal indication may insert the plug 41 of such trunk into the jack 40. This act serves to effect the movement of sequence switches SS_2 and SS_3 95 into position 14 and into ringing position, respectively, as disclosed for example, in the patent above referred to. The lamp 27 is thereupon arranged to burn steadily over a circuit from grounded battery, lamp 27, contact 102 of sequence switch SS_2 between positions 3 to 16 to ground, as disclosed in said 100 patent and remains steadily lighted until the ringing is completed as hereinafter described. The switchman is now signalled 105 through the application of alternating ringing current to the tip and ring conductors of the plug 41, over a circuit including the source of ringing current 103, contact 104 110 in position 13, the tip contacts of plug 41 and jack 40, conductor 45, right-hand winding of relay 44, condenser 46, conductor 47, the ring contacts of the jack 40 and plug 41 115 and the contact 105 in position 13 to said source 103. The consequent operation of relay 44 illuminates the lamp 48 and provides a direct current locking circuit for relay 44 extending from grounded battery, lamp 48, contact and left-hand winding of relay 44, and middle contacts of a listening key 49 120 associated with the switchman's trunk to ground. If the plugs 50 and 51 of the switchman's set are not already engaged with the jacks 52 and 53 of his trunk, the switchman, on observing the illumination 125 130

of lamp 48, inserts these plugs or plugs of a similar switchman's set therein and moves the key 49 to listening position.

This act automatically disconnects the 5 ringing current, and moves the contacts of sequence switch SS_3 , into position 17, in which position the lamp 27 is extinguished and the controlling circuit of the calling supervisory lamp 59 extended to the contact 10 of relay 92. This relay was actuated upon the insertion of the plug 41 into jack 40 over a circuit extending from grounded battery, winding of relay 92, sleeve contacts of plug 41 and jack 40, and resistance to ground. 15 The contact of relay 92 is thus closed during ringing, but completes no circuit until sequence switch contact 43 is moved into position 17, upon the switchman moving the key 49 to listening position. As soon as this is 20 done however a circuit is completed extending from battery, lower right-hand winding of coil 56, winding of relay 58, ring contacts of plug 41 and jack 40, conductor 47, upper contacts of key 49, right windings of transformer coil 99, lower contacts of key 49, conductor 45, tip contacts of jack 40 and plug 41, and upper right winding of coil 56 to the other side of battery. Relay 58 is thereby 25 operated thus short-circuiting lamp 59 and preventing its illumination so long as this 30 circuit is maintained. The switchman can signal the answering operator however by opening and closing the listening key 49, thus alternately opening and closing the circuit 35 through the relay 58. Its contact is correspondingly opened and closed, and when opened removes the short circuit about the lamp 59 to permit its illumination over a circuit from grounded battery, resistance 97, 40 lamp 59, contact 43 of sequence switch SS_3 , in position 17, and contact of relay 92 to ground. The resulting flashing of the lamp 59 serves to indicate that the switchman desires to communicate with the operator, being 45 substantially the same operation of the signals and their meaning as in a connection between a calling and a called subscriber.

Although the insertion of the plug 41 into jack 40 effects the movement of the contacts 50 of sequence switch SS_2 out of their seventh or listening-in position into their fourteenth or talking position, as disclosed in before-mentioned patent, means are available to the operator as therein described which will 55 upon operation effect the movement of the sequence switch SS_2 , again to its listening-in position and inasmuch as the key 49 is in its listening position such an act by the operator will complete telephonic circuits for 60 intercommunication between the operator and the switchman. On obtaining this connection the operator informs the switchman of the permanent signal on the trunk used in the connection.

65 The operator would effect the movement

of the contacts of sequence switch SS_2 again to its fourteenth or listening-out position, and the switchman would establish connection of plugs 50 and 51 of a switchman's set with the jacks 62 and 63 of a tone testing circuit, 70 preferably common to all the switchmen's trunks, in order to locate the line finder involved in the permanent signal connection. The same or another switchman's set can be used for this purpose, and the circuit of the 75 switchman's trunk is such that the disengagement of the plugs 50 and 51 from the jacks 52 and 53 does not disturb the circuit previously traced to maintain the supervisory relay 58 energized to prevent illumination of the lamp 59. The transformer coil 99 and jacks 52 and 53 may however be common to a number of switchmen's 80 trunks, and connected to the individual trunks by the movement of the key 49 individual to a particular trunk with which connection is desired.

In the present system it is possible for one switchman to answer calls over the switchman's trunk and another switchman 90 to simultaneously search for line finders involved in permanent signal connections. The switchman answering a call over a switchman's trunk, on being informed of the permanent signal connection, and desiring 95 to disconnect from such trunk, as for example to answer a call over another trunk, would move holding key 55 into its closed position and also move the key 49 of the 100 trunk in use out of listening position. The operation of key 49 disconnects the coil 99 from the trunk originally used and leaves it free to be connected to another switchman's trunk by movement of the key 49 individual to such other trunk. The closure of key 55 105 provides a holding circuit through the relay 58 to prevent the lamp 59 giving a disconnect signal at this time; this circuit extending from battery, lower right winding of coil 56, winding of relay 58, ring contacts of 110 plug 41 and jack 40, conductor 47, upper contacts of key 55, winding of retardation coil 57, lower contacts of key 55, conductor 45, tip contacts of jack 40 and plug 41, and upper right-hand winding of coil 56 to the 115 other side of battery. Under these conditions none of the lamps 27, 59 and 60 are lighted, and since this condition is maintained until after the involved line finder has been located, consequent annoyance of 120 the operator by false signals during the testing operation is thereby prevented.

Referring to the testing operation, the insertion of plug 50 into the jack 62 completes a governing circuit for a tone generator 64, 125 this circuit extending from grounded battery, winding of a relay 65, conductor 66, and upper contacts of jack 62 to ground. The energization of relay 65 completes a circuit to operate the tone generator 64, this 130

- circuit extending from grounded battery, thence in parallel through the winding of the motor and the direct current commutator of the motor, to conductor 68 and contact 5 of relay 65 to the ground. Another switch 70 may be provided to close another operating circuit for the tone generator 64, if it is desired to operate this generator independently of the jack 62 and relay 65.
- 10 The tone generator 64 develops alternating current, the frequency thereof being preferably such as to produce a tone which can be readily distinguished from currents of other frequencies which may be encountered in testing over the multiple terminals of line finders engaged at the time; the alternating current thus developed flowing through the primary winding of a transformer 71 and inducing corresponding currents in the secondary winding thereof.
- 15 Each of the switchman's trunks has a tone key 72 individual thereto, and in testing over such trunk this key is closed. Under these conditions the insertion of the plug 51 into the jack 63 completes a tone circuit extending from the grounded secondary winding of repeating coil 71, conductor 73, resistance 74, lower contacts of jack 63, left-hand contacts of tone key 72, conductor 47, ring contacts 20 of jack 40 and plug 41, winding of supervisory relay 58, and lower right-hand winding of repeating coil 56 through battery to ground. A parallel branch of this circuit extends from the conductor 73, through the right-hand contacts of tone key 72, conductor 45, tip contacts of jack 40 and plug 41, and upper right-hand winding of repeating coil 56 to ground. The resistance 74 is inserted in the parallel branch including the ring contacts of the jack 40 and plug 41 to prevent too great a flow of direct current over a circuit completed upon the insertion of plug 41 into jack 40 and extending from battery, lower right-hand winding of coil 56, winding of relay 58, ring contacts of plug 41 and jack 40, conductor 47, left-hand contacts of key 72, lower contacts of jack 63, resistance 74, right-hand contacts of key 72, conductor 45, tip contacts of jack 40 and plug 41, and upper right-hand winding of coil 56 to battery. The several windings of the transformer or repeating coil 56, preferably contain substantially the same number of turns, on account of its use for two way telephonic transmission as well as for testing currents, although this particular relation between the different windings is not essential to the present invention.
- 25 A transformer coil 76 has its primary winding arranged in a circuit connection bridged across the tip and ring brushes of the brush set 36, and condensers 77 and 78 are positioned in this connection intermediate the primary winding and the respective brushes. The primary winding of the coil 76 is non-symmetrically divided by being grounded at an intermediate point of its winding so as to include a considerably greater number of turns in the tip side. The secondary winding of the transformer 70 coil 76 is included in a looped circuit extending from this winding, sleeve contacts of jack 62 and plug 50, receiver 79 of the switchman's set, and sleeve contacts of plug 51 and jack 63 back to the secondary winding of the repeating coil 76. The transmitter 80 of the switchman's set is preferably left out of circuit during testing as there is no reason to use it during the actual testing.
- 30 The switchman in searching for the line finder connected to the involved subscriber's line, moves his brush set 36 over the testing bank 35 until it encounters the terminal set 39 of line finder LF having testing current 85 thereon, which fact will be indicated to the switchman by the production of a characteristic tone in his receiver 79 corresponding in frequency to the frequency of the testing currents developed by the tone generator 64. 90
- 35 Upon the engagement of the brush set 36 with the terminal set 39, the secondary windings of the repeating coil 56 will be connected with the divided-primary winding of the transformer coil 76 by three conducting paths for alternating current, namely, the tip conductor of the trunk selector line finder, test terminal, brush and condenser 77; the ring conductor of the trunk selector line finder, test terminal, brush, and condenser 78, and ground. Three fluctuating current circuits are accordingly possible between the secondary windings of the repeating coil 56 and the primary winding of transformer coil 76, the first 95 including the upper secondary winding of the repeating coil 56, the tip conducting path, upper portion of primary winding of transformer 76, and ground to the other side of such secondary winding, the second circuit including the battery and other secondary winding of coil 56, the ring conducting path, the lower portion of such primary winding, and ground to the other side of such battery, and the third circuit including both secondary windings of coil 56 and intermediate battery in series with the tip conducting path, entire primary winding of coil 76 and the ring conducting path. The unbalancing of the primary windings 100 is to produce a non-symmetrical circuit arrangement between the repeating coil 56 and the transformer coil 76, and is such as to insure a resultant flow of fluctuating current to operate the receiver 79, so long as fluctuating currents continue to flow in any one or more of the three circuits. As a result of the non-symmetrical arrangement, so long as none of the three conducting paths are open or short-circuited to fluctu-

- 50 115
- 55 120
- 60 125
- 65 130

ating currents, and fluctuating currents are developed in the secondary windings of the repeating coil 56, corresponding current will flow over each of the three conducting paths, and each of the three mentioned circuits will be maintained. Short circuiting between any two of the three conducting paths will still leave at least one of the three circuits operative to produce an effective flow of current in the secondary winding of the transformer coil 76 to operate the receiver 79, and it is only when all three of these conducting paths are directly short circuited together by a connection of practically negligible resistance that all three of these circuits can be effectively destroyed and the operation of the receiver 79 prevented; experiment having shown that a flow of testing current can be detected in the receiver 79 when all three of the conducting paths have been joined together through a short circuiting connection, the resistance of which was of low value. From the foregoing description it will be evident that flux produced in the core of the repeating coil 56 thus produces flux in the core of the transformer coil 76 by means of currents flowing over each of these three conducting paths, so long as two or all of the three circuits are effectively maintained.

The tip and ring conductors and the ground connection of the trunk line are involved in the three conducting paths noted, and the tip and ring conductors of the trunk line involved are, under these conditions, connected through the corresponding brushes and conductors of the selector and line finder involved with the tip and ring terminals to which the line conductors 10 and 11, respectively, are connected. Should the permanent signal be caused by a grounding of the ring line conductor 11, the ring and ground conducting paths mentioned are short circuited together, and while the second and third circuits are thus effectually destroyed, the first circuit over the tip and ground conducting paths is effectively maintained, and flux is developed thereby in the core of the transformer 76 by the passage of fluctuating currents through the upper portion of the primary winding thereof. This flux develops a fluctuating current in the secondary winding of the transformer 76, and thus effects the operation of the receiver 79, so that the engagement of the brush set 36 upon the terminal set 39 of the line finder it is desired to locate will be readily detected. On some types of lines it is possible to obtain a permanent signal when the tip line conductor is grounded, and in such cases the tip and ground conducting paths are short circuited together. This results in effectually destroying the first and third circuits, but the second circuit over the ring and ground conducting

paths is effectively maintained, and flux is developed thereby in the core of the transformer 76 by the passage of fluctuating currents through the lower portion of the primary winding. This flux similarly effects the operation of the receiver 79 to detect the engagement of the brush set 36 with the terminal set of the line finder involved. A permanent signal may also result from a short circuiting together of the line conductors 10 and 11, and in such cases the tip and ring conducting paths are short circuited together. This to all intents effectually destroys the third circuit, but the first and second circuits are still effectually maintained, the first over the tip and ground conducting paths, and the second over the ring and ground conducting paths. The passage of the fluctuating currents in the first circuit through the upper portion of the primary winding of transformer 76 develops flux in the core thereof, while the passage of the fluctuating currents in the second circuit through the lower portion of this primary winding develops flux in the core thereof which is always opposed to the flux developed in the upper portion of this primary by the current in the second circuit. Due however to the unsymmetrical arrangement previously described, these fluxes are unbalanced, and the resultant flux develops a fluctuating current in the secondary winding of the transformer 76, which in turn operates the receiver 79 in accordance with the impressed frequency. When the permanent signal arises from a subscriber leaving the receiver of his set removed from the hook switch, the situation is for all practical purposes, the same as that existing when the line conductors 10 and 11 are short-circuited, and accordingly no special explanation is considered necessary.

It may however occasionally happen that the condition causing a permanent signal will clear itself subsequent to connection to the testing position, but before the brush set 36 has been engaged with the terminal set of the line finder involved. In this event all of the three circuits between the secondary windings of the repeating coil 56 and the primary winding of the transformer coil 76 are effectually established with the engagement of the brush set 36 with the terminal set of such line finder. No short circuit exists between any two or more of the three conducting paths, and the passage of the fluctuating currents over each of these circuits through such portion or portions of the primary winding of transformer 76, as are included in the respective circuits, results in the production of corresponding flux in the core of this transformer. The flux produced by two of these circuits will lead a direction opposite to

that possessed by the flux which the other one of the three circuits develops at the same instant, but a preponderance of flux exists in one direction at such instant, and 5 provides resultant flux effective to develop fluctuating current in the secondary winding of the transformer 76 to operate the receiver 79, in accordance with the frequency of the testing current, thus indicating the engagement of the brush set 36 with 10 the terminals of a line finder it is desired to locate as previously described.

The unsymmetrical circuit arrangement described thus insures alternating signaling current reaching and operating the receiver 79, irrespective of whether the permanent signal arises from the receiver being off the hook switch, the short-circuiting of the conductors 10 and 11, or the grounding of one 20 or the other of these conductors, and also in event of the removal of the condition causing such permanent signal prior to the location of the line finder involved.

The number 4 indicated on the designation strip 37 by the pointer 38 at this time shows the line finder 4, identified as LF on the drawing, to be the one involved. This line finder is at once visited and the number of the terminal set on which its engaged 30 brush set rests noted. From the position of this terminal set in the contact bank, the number of the line represented thereby may often be directly determined or the number may be found by consulting a list or chart 35 of line finder terminals. As soon as the number of this line is determined, the switchman has a plug 84 of a trouble cord 85, having its sleeve conductor associated with a suitable source of alternating current 40 inserted into a multiple jack 87 of the line A. In practice the tone generator 64 can serve as this source, in which case another transformer 86 is preferably provided, having its primary winding arranged in the output circuit with the generator 64, and its 45 secondary winding connected to the sleeve of the plug 84. On the insertion of the plug 84 into the jack 87, tone current is placed upon all the sleeve multiples of line A, and produces a distinctive tone in an operator's receiver, upon testing the sleeve multiple of line A with the tip of a calling plug of a cord or trunk circuit to determine whether or not line A is in proper condition to receive a call. The character of the tone received indicates line A to be in trouble, and warns operators against connecting therewith. Obviously, a separate tone generator can be used to supply current to the 55 trouble cords 85, if desired. The sleeve terminals of the line finder multiples of line A also have this current placed on them, but inasmuch as the cut-off relay 13 of line A is operated upon the insertion of jack 84 into 60 jack 87, over a circuit extending from

grounded battery, secondary winding of transformer 86, conductor 88, resistance 89, sleeve contacts of plug 84 and jack 87, conductor 15, and winding of relay 13 to ground, to disconnect the line relay 12 and 70 the battery associated therewith from the conductors 10 and 11, line A, will not interfere with the operation of line finder LF after such line finder is restored to its normal position; nor with other line finders, 75 inasmuch as the operation of relay 13 prevents subsequent actuation of relay 12 and consequent closure of the starter wire circuit.

The restoration of the involved line finder, selector, and operators' and switchmen's 80 trunks to their normal condition may be accomplished in any suitable manner. One such method is for the switchman to see that his set is connected to the jacks 52 and 53 and that the tone key 72 of the trunk involved is open. He next opens the holding key 55 of the switchman's trunk used in the connection, and alternately closes and opens the key 49 of this trunk to flash the operator through the medium of the lamp 59 as 90 earlier described. The operator, in response, effects the connection of her set with the trunk connected with the selector, as before explained, and the key 49 is now maintained in listening position. The switchman then directs the operator to withdraw the plug 41 from the jack 40. The operator thereupon takes down the connection and the selector CS, as well as the operators' and switchmen's trunks involved therein, are restored 95 to normal condition ready for subsequent use as disclosed in the previously noted copending patent application.

The above-described method is suitable under ordinary operating conditions, but in order to further economize the time of the answering operators during periods of very heavy traffic, a number of tone jacks 90 may be provided, convenient to the answering operators. Any trunk having a permanent signal thereon would have the plug 41 thereof inserted into a tone jack 90, thereby operating a relay 91, over a circuit extending from grounded battery, winding of relay 92, sleeve contacts of plug 41 and jack 90, conductor 93 and winding of relay 91 to ground. The operation of relay 91 in turn effects the illumination of a lamp 94 at the switchman's position, thereby indicating that a trunk having a permanent signal thereon has been 110 plugged into tone jack 90; while the operation of the relay 92 prepares a circuit for the lamp 59, as previously explained.

This relay 91 and lamp 94 may, if desired, be common to a large number of tone 125 jacks 90. Plugging into jack 90 completes a tone circuit extending from the grounded secondary winding of repeating coil 71, conductor 95, resistance 96, ring contacts of jack 90 and plug 41, winding of supervisory re- 130

lay 58, and lower right-hand winding of repeating coil 56, through battery to ground. A parallel branch of this circuit extends from the conductor 95, tip contacts of jack 90 and plug 41, and upper right-hand winding of repeating coil 56 to ground. The resistance 96 serves the same purpose as the resistance 74 where the switchman's trunk is employed in testing, and prevents too great a flow of direct current over the direct current circuit extending from grounded battery, lower right-hand winding of coil 56, winding of relay 58, ring contacts of plug 41 and jack 90, resistance 96, conductor 95, and secondary winding of transformer 71, to ground. Upon the insertion of plug 41 into jack 90, ringing current is automatically applied, as previously described, but due to the completion of the direct current circuit just mentioned, the contacts of the sequence switch SS₂ are moved into their position 17, but without lighting the lamp 59, inasmuch as the supervisory relay 58 is energized under these conditions. The lamp 27 is extinguished on the movement of contact 102 of switch SS₂ into position 17, leaving the lamps, all extinguished during subsequent testing operations.

The switchman observing the illumination 30 of the lamp 94, would see that plugs 50 and 51 of a switchman's set were in the jacks 62 and 63, as previously described, to insure the actuation of the relay 65 and consequent operation of the tone generator 64 and generation of fluctuating testing currents in the secondary winding of the repeating coil 71, as previously described. The switchman then searches over the contact bank 35 to locate the line finder connected to the line 40 causing the permanent signal, and on determining this line finder, proceeds to find the number of the line represented by the terminal set engaged by the brush set thereof. He then proceeds to have trouble tone as well 45 as direct current placed on the sleeve terminals of this line, in order that such line will test in trouble, and in order that the line relay 13 of such line will be operated, as previously described.

50 The line finder may then be manually restored to its normal position, which effects the restoration of the selector CS to normal and the movement of the contacts of sequence switch SS₂ to position 1. A disconnect signal results from the opening of the operating circuit of the relay 69 on disengagement of the finder and selector brush sets 16 and 19 from the terminal sets 18 and 21, respectively, and the consequent illumination 55 of the lamp 60 to indicate disconnection is desired, as disclosed in the copending Williams patent application. The lamp 59 is not lighted under these circumstances, but the operator on noting that the plug 41 of 60 the involved trunk is in a trouble jack 90,

disconnects therefrom, extinguishing lamp 94 at the switchman's position, provided no other trunks are engaged in corresponding tone jacks 90, and effecting the restoration of the trunk to normal condition.

70 The line finder LF, selector CS, and the apparatus used in locating the involved line finders are now in their normal condition ready for subsequent use, and line A is arranged to test in trouble, and prevented from 75 again connecting with any of the line finders until the trouble has been located and line A restored to its normal condition.

80 From the above description it will be apparent that if a number of different operators' trunks having permanent signals thereon are plugged into tone jacks 90, the switchman can locate all the line finders involved by testing over the terminal sets in the bank 35 and noting all of the line finders 85 having tone current on their terminal sets in the bank 35. These line finders would be visited, and the particular lines involved noted, and removed from service as previously explained. This arrangement is of 90 aid in quickly locating a number of lines having permanent signals thereon, and preventing these lines tying up line finders and cord selectors, which serve as percentage apparatus for a number of other lines. It will 95 be further apparent that with the present system it is possible to simultaneously search for line finders associated with trunks connected to switchmen's trunks and for line finders associated with trunks directly engaged with tone jacks 90; thus insuring a 100 flexibility of operation desirable in systems of this character.

What is claimed is:

1. An electrical testing system comprising 105 pairs of banks of terminals, selectors permanently connected in pairs and adapted to cooperate with said banks respectively, a test terminal for each pair of selectors, means to supply testing current to the test terminal 110 of a pair of operated selectors, and means cooperating with said test terminals to indicate the particular pair having testing current upon the test terminal thereof.

2. An electrical testing system comprising 115 a first group of sets of apparatus, a second group of sets of apparatus, a plurality of sets of automatically operated connecting apparatus common to both of said groups to connect a set in the first group with a set 120 in the second group, a test terminal individual to each of said plurality of sets, means to supply testing current to the test terminal of a set of connecting apparatus connecting a set of the first group with a set 125 of the second group, and means cooperating with said test terminals to indicate the particular set of connecting apparatus involved in such connection.

3. An electrical testing system comprising 130

- a group of lines extending to a plurality of different positions, a plurality of sets of automatically operated connecting apparatus common to said groups, and each arranged to selectively connect with any line of said group, a test terminal individual to each of said sets, means to supply testing current to a line of said group with which one of said sets is connected at the position at which such line terminates, and means cooperating with said test terminals to indicate the particular one of said sets involved in such connection. 5
4. An electrical testing system comprising a group of calling lines, a group of trunk lines, a plurality of sets of automatic connecting apparatus common to each of said groups and selectively operable to connect any one of said calling lines to any one of said trunk lines, a test terminal individual to each of said sets, means to supply testing current to the test terminal of a set connecting a calling line to a trunk line, and means cooperating with said test terminals to indicate the particular set involved in such connection. 10
5. An electrical testing system comprising a group of calling lines, a group of trunk lines, a plurality of sets of automatic connecting apparatus common to each of said groups and selectively operable to connect any one of said calling lines to any one of said trunk lines, a test terminal individual to each of said sets, means to supply testing current to a trunk line with which one of said sets is connected, and means cooperating with said test terminals to indicate the particular set involved in such connection. 15
6. An electrical testing system comprising a group of calling lines, a plurality of automatic line finders common to said group and selectively operable to connect any selected one of said finders to any one of said calling lines, a plurality of trunk lines, a plurality of selectors common to said group of trunk lines associated with said plurality of finders and each operable to connect with any selected one of said trunk lines upon connection of the finder with which said selector is associated with a calling line, a test terminal individual to each of said finders, means to supply testing current to a trunk line connected to a trunk selector, and means cooperating with said test terminals to indicate the particular finder involved in such connection. 20
7. An electrical testing system comprising a group of subscribers' lines, a group of trunk lines extending to an operator's position, a plurality of sets of connecting apparatus common to both of said groups and each selectively operable to connect any line of one group to any line of the other group, a test terminal individual to each of said sets located at a testing position, connecting means to extend said trunk lines to said testing position, means to supply testing current through said connecting means to a trunk line extended to said testing position, and means cooperating with said test terminals to indicate the particular set connected to a trunk line extended to said testing position. 25
8. An electrical testing system comprising a group of subscribers' lines, a group of trunk lines extending to an operator's position, a plurality of sets of connecting apparatus common to both of said groups and each selectively operable to connect any line of one group to any of the other group, a test terminal individual to each of said sets located at a testing position, a plurality of connecting circuits between said operator's position and said testing position to connect said trunk lines to said testing position, means individual to each of said connecting circuits to supply testing current to a trunk line connected therewith, and means cooperating with said test terminals to indicate the particular set connected to a trunk line connected with a connecting circuit. 30
9. An electrical testing system comprising a group of subscribers' lines, a group of trunk lines extending to an operator's position, a plurality of sets of connecting apparatus common to both of said groups and each selectively operable to connect any line of one group to any line of the other group, a test terminal individual to each of said sets located at a testing position, a plurality of connecting circuits between said operator's position and said testing position to connect said trunk lines to said testing position, means individual to each of said connecting circuits to supply testing current to a trunk line connected therewith, and means common to said connecting circuits and cooperating with said test terminals to indicate the particular sets connected to trunk lines connected with said connecting circuits. 35
10. An electrical testing system comprising a group of subscribers' lines, a group of trunk lines extending to an operator's position, a plurality of sets of connecting apparatus common to both of said groups and each selectively operable to connect any line of one group to any line of the other group, a test terminal individual to each of said sets located at a testing position, a source of testing current, means at said operator's position available to said trunk lines through which testing current is applied to a trunk line connected therewith, a signal at said testing position associated with said last-named means and actuated upon the connection of a trunk line with such means, and means cooperating with said test terminals to indicate the particular set connected to a trunk line connected with the means through which testing current is applied to a trunk line. 40

11. An electrical testing system comprising a group of subscribers' lines, a group of trunk lines extending to different operators' positions, a plurality of sets of connecting apparatus common to both of said groups and each selectively operable to connect any line of one group to any line of the other group, a test terminal individual to each of said sets located at a testing position, a source 10 of testing current, means at the operators' positions and available to said trunk lines through which testing current is applied to trunk lines connected therewith, a signal at said testing position associated with last 15 mentioned means and actuated upon connection of a trunk line with such means, and means common to said means through which testing current is applied and cooperating with said test terminals to indicate the particular sets connected to trunk lines connected with the means through which testing current is applied.

12. An electrical testing system comprising a group of subscribers' lines, a group of 25 trunk lines extending to an operator's position, a plurality of sets of connecting apparatus common to both of said groups and each selectively operable to connect any line of one group to any line of the other group, 30 a test terminal individual to each of said sets located at a testing position, a source of testing current, means at the operator's position to which said trunk lines extend and available to such trunk lines through which 35 testing current is applied to any of said trunk lines connected therewith, a signal at said testing position associated with said last-mentioned means and actuated upon connection of a trunk line with such means, and 40 testing means common to said means through which testing current is applied and cooperating with said test terminals to indicate the particular sets connected to trunk lines connected with the means through which 45 testing current is applied.

13. An electrical testing system comprising a group of lines, a plurality of sets of connecting apparatus common to said lines and each selectively operable to connect with 50 any of said lines, a test terminal individual to each of said sets located at a testing position, a source of testing current, connecting means to extend said lines to said testing position, means available to said lines through 55 which testing current is applied to a line connected therewith, a signal at said testing position associated with said last named means and actuated upon connection of a line with such means, means to apply testing 60 current through said connecting means to a line extended to said testing position, and means common to said connecting means and to said means available to said lines cooperating with said test terminals to indicate the particular sets connected to lines 65

connected with said connecting means and with said means available to said lines.

14. An electrical testing system comprising a group of sets of apparatus, a plurality of sets of other apparatus common to said group and arranged to selectively connect with any set of said group, a test terminal individual to each of said plurality of sets, contact means to selectively engage said test terminals, a source of testing current, means 70 to apply testing current to the test terminal of a set connected with a set of said group, detecting means associated with said contact means to detect the engagement thereof with a test terminal having testing current applied thereto, and means to directly identify the particular set upon the test terminal of which testing current is detected.

15. An electrical testing system comprising a first and a second transformer coil 85 each having a core and a winding operatively associated with its respective core, three conducting paths to connect three different points of the winding of the first coil to three different points of the winding of the second coil to join said windings in nonsymmetrical electrical arrangement, three circuits each including a different pair of said conducting paths and different arrangements of each of said windings, and means 90 to develop flux in the core of one of said coils to produce a flow of current in each of the three circuits, said flow of current serving to develop a resultant flux in the core of the other coil.

16. An electrical testing system comprising a first and a second transformer coil, each having a core and a winding operatively associated with its respective core, three conducting paths to connect three different points of the winding of the first coil to three different points of the winding of the second coil to join said windings in nonsymmetrical electrical arrangement, three circuits each including a different pair of said 105 conducting paths and different arrangements of each of said windings, and means to develop flux in the core of one of said coils to produce a flow of current in such of the three circuits as are effectively maintained; the flow of current in such circuits as are effectively maintained serving to develop an effective flux in the core of the other coil.

17. An electrical testing system comprising a first and second transformer coil, each having a core and a winding operatively associated with its respective core, three conducting paths to connect three different points of the winding of the first coil to three different points of the winding of the second coil to join in nonsymmetrical electrical arrangement, three circuits each including a different pair of said conducting paths and different arrangements of each of said windings and arranged in such a way 115 120 125 130

that at least one of said circuits is effectively maintained on short circuiting together of any two of the three conducting paths, and means to develop a flow of current in such 5 of the three circuits as are effectively maintained on short circuiting together of two of the three conducting paths; the flow of currents in such of the circuits as are effectively maintained serving to develop an effective 10 flux in the core of the coil.

18. An electrical testing system comprising a first and a second transformer coil, each having a core and a winding operatively associated with its respective core, 15 three conducting paths to connect three different points of the winding of the first coil to three different points of the winding of the second coil to join said windings in non-symmetrical electrical arrangement; three 20 circuits each including a different pair of said conducting paths and different arrangements of each of said windings and arranged in such a way that at least one of said circuits is effectively maintained on short circuiting together of two of the three conducting paths, and means to develop flux in the core of one of said coils to develop a flow of current in such of the three circuits as are effectively maintained on the short circuiting together of two of the three conducting paths; the flow of current in such of the circuits as are effectively maintained serving to develop an effective flux in the core of the other coil. 25

19. An electrical testing system comprising a first and a second transformer coil, each having a core and a winding operatively associated with its respective core, three conducting paths to connect three different points of the winding of the first coil to three different points of the winding of the second coil to join said windings in non-symmetrical 30 electrical arrangement; three circuits each including a different pair of said conducting paths and different arrangements of each of said windings and arranged in such a way that one of said circuits is effectively maintained on short circuiting together of two of the three conducting paths, and means to develop flux in the core of one of said coils to develop a flow of current in the circuit effectively maintained on the short circuiting together of two of the three conducting paths; the flow of current in the circuit effectively maintained serving to develop an effective flux in the core of the other coil. 35

40

symmetrical electrical arrangement, three circuits each including a different pair of said conducting paths and different arrangements of each of said windings and arranged in such a way that two of said circuits are effectively maintained on short circuiting together of two of the three conducting paths, and means to develop flux in the core of one 45 of said coils to develop a flow of current in the two circuits effectively maintained on the short circuiting together of two of the three conducting paths; the flow of current in the two circuits effectively maintained serving to develop a resultant flux in the core of the other coil. 50

20. An electrical testing system comprising a first and a second transformer coil, each having a core and a winding operatively associated with its respective core, three conducting paths to connect three different points of the winding of the second coil to join said windings in nonsymmetrical 60 electrical arrangement, three circuits each including a different pair of said conducting paths and different arrangements of each of said windings and arranged in such a way that one of said circuits is effectively maintained on short circuiting together of two of the three conducting paths, and means to develop flux in the core of one of said coils to develop a flow of current in the circuit effectively maintained on the short circuiting together of two of the three conducting paths; the flow of current in the circuit effectively maintained serving to develop an effective flux in the core of the other coil. 65

70

In witness whereof, we hereunto subscribe 80 our names this 30th day of January, A. D. 1919.

SAMUEL B. WILLIAMS, JR.
HERBERT L. BOSTATER.
